UNITED STATES PATENT OFFICE.

ALFRED A. HUNTING, OF SALEM, MASSACHUSETTS.

DRYING CAN OR CYLINDER.

SPECIFICATION forming part of Letters Patent No. 700,776, dated May 27, 1902.

Application filed August 5, 1901. Serial No. 70,915. (No model.)

To all whom it may concern:

Be it known that I, ALFRED A. HUNTING, a citizen of the United States, residing in Salem, in the county of Essex and State of Massachusetts, have invented an Improvement in Drying Cans or Cylinders, of which the following description, in connection with the accompanying drawings, is a specification, like characters on the drawings representing like parts.

10 This invention relates to drying cylinders or cans, and is an improvement upon the drying can or cylinder shown and described in United States Patent No. 666,477, granted to me January 22, 1901.

15 The present invention has for its object to increase the efficiency of the drying cylinders or cans, such as shown and described in the patent referred to, when said cylinders or cans are made of substantially large size—
20 for instance, from thirty inches in diameter and upward. For this purpose I provide the hollow trunnion through which the water of condensation is discharged out of the can or cylinder with means to accelerate such discharge, and prefer to employ a spiral rib or web which will impart to the water a rifle motion and force it out of the hollow trunnion at a speed sufficient to insure the substantially large volume of water in the large
25 cylinder or can being discharged out therefrom. To further facilitate the discharge of the substantially large volume of water of condensation, I provide an unobstructed passage for the water from the spirally-arranged
30 open gutter on the inner circumference of the can to the discharge-trunnion, which is obtained by making the reservoir intermediate the said gutter and the hollow trunnion curved, as will be described, so that as the
35 water is carried into the said reservoir it follows the curved form of the latter and its current or flow is not impeded, obstructed, or checked on its way to the discharge-trunnion. The spiral web is arranged with relation to
40 the outlet-mouth of the reservoir in such manner, as will be described, that the water is prevented or at least restrained from returning to the reservoir during each revolution of the drying can or cylinder. These and
45 other features of this invention will be pointed out in the claims at the end of this specification.

Figure 1 is a front elevation with parts broken out of a drying can or cylinder embodying this invention; Fig. 2, an end elevation of the can shown in Fig. 1; Fig. 3, a vertical section on the line 3 3, Fig. 2; Fig. 4, a cross-section on the line 4 4, Fig. 3; Fig. 5, a cross-section of a modified form, and Fig. 6 a vertical section of a modification to be referred to.

55 In Fig. 1 I have represented a substantially large drying can or cylinder, such as used in paper-mills. The cylinder or body *a* in this case is made of cast-iron and is provided at its opposite ends with substantially large openings, which are closed by cast-iron heads *b* *c*, secured to the body *a*, as by bolts or screws *d*. The can or cylinder *a* has attached to its inner circumference a spirally-arranged open gutter *e*, extended from near the steam-inlet end of the can to the discharge end thereof, substantially as shown and described in the patent above referred to.

60 In large-size cans or cylinders having a diameter of thirty inches and upward the volume of water of condensation picked up by the gutter *e* and conveyed into a reservoir *f* at the discharge end of the can is so great that opportunity is not afforded for this water to pass out of the can or cylinder, especially when the latter is revolving at a high or substantially high speed, and as a result if the high speed is maintained the can in time is filled or substantially filled with water of condensation, thereby necessitating the slowing down of the machine, and consequently reducing the output of the machine.

65 The present invention has for its object to provide means whereby the water of condensation is discharged out of the can at such rate as to insure the can or cylinder being kept free from water even when revolving at a high or substantially high speed, thereby obtaining an efficient drying of a maximum 70 quantity of material. For this purpose I provide the discharge-pipe *g*, extended from the reservoir *f* through the hollow trunnion *h*, with a spirally-arranged rib or web *i*, which imparts a rifling motion to the water in the discharge-pipe and accelerates its rate of discharge. The web or rib *i* is arranged with relation to the outlet-mouth of the reservoir so as to extend partially across said mouth, as

shown in Figs. 4 and 5, so that as the can is revolved in the direction indicated by arrow 20 in Figs. 4 and 5 the water will be restrained or checked from backing up and returning into the reservoir. To still further facilitate the discharge of the water, the front and rear walls 4 5 of the reservoir are made curved, as represented in Figs. 4 and 5, so that the flow or current of the water on its passage through 10 the reservoir is not checked or obstructed.

In Fig. 6 I have represented a large size of can or cylinder, such as used in cloth-mills, in which the cylindrical body is made of sheet metal and the heads are made of cast metal, 15 whereas in Figs. 1, 2, and 3 the can is made of cast metal.

In Fig. 5 the reservoir *f* is shown as provided with a pipe or nozzle *j*, which may be employed with the cans or cylinders having 20 sheet-metal heads, which are in this case provided with a cast trunnion.

I claim—

1. The combination with a drying can or cylinder provided with a hollow trunnion, of 25 a reservoir communicating with said trunnion, a spirally-arranged open gutter or conductor on the inner side of the can or cylinder communicating with said reservoir, and means within said hollow trunnion for accelerating the discharge of water of condensation, substantially as described.

2. The combination with a drying can or cylinder provided with a hollow trunnion, of a curved reservoir communicating with said trunnion, a spirally-arranged open gutter or 35 conductor on the inner side of the can or cylinder communicating with said reservoir, and a spirally-arranged web or rib within said hollow trunnion, substantially as described.

3. The combination with a drying can or 40 cylinder provided with a hollow trunnion, of a reservoir communicating with said trunnion, a spirally-arranged open gutter or conductor on the inner side of the can or cylinder communicating with said reservoir, and a 45 web or rib within the hollow trunnion and extended across the outlet-mouth of said reservoir, substantially as described.

4. The combination with a drying can or cylinder provided with a hollow trunnion and 50 with means for conveying water of condensation within the can to said hollow trunnion, of means for accelerating the discharge of the water of condensation through said hollow trunnion, substantially as described.

In testimony whereof I have signed my name to this specification in the presence of two subscribing witnesses.

ALFRED A. HUNTING.
